DESIGN FOR A CONDIMENTS RECEPTACLE

Harry W. Keuper, Fort Thomas, Ky., assignor to
George H. Lackner, Cincinnati, Ohio

Application March 26, 1945, Serial No. 118,708

Term of patent 14 years

(Cl. D44—22)

To all whom it may concern:

Be it known that I, Harry W. Keuper, a citizen of the United States and a resident of Fort Thomas, in the county of Campbell and State of Kentucky, have invented a new, original, and ornamental Design for a Condiment Receptacle, of which the following is a specification, reference being had to the accompanying drawing, which forms a part thereof.

In the drawing:

Fig. 1 is a perspective view of a condiment receptacle showing my new design;

Fig. 2 is a top plan view thereof;
Fig. 3 is an end elevational view of the condiment receptacle with the cap removed; and
Fig. 4 is an end elevational view of the cap portion of the condiment receptacle.

I claim:

The ornamental design for a condiment receptacle, substantially as shown and described.

HARRY W. KEUPER.
